(57) **CLAIM**

The ornamental design for a table for a conferencing environment, as shown and described.

DESCRIPTION

FIG. 1 is an isometric view of a table for a conferencing environment showing the new design.

FIG. 2 is a top view of the new design.

FIG. 3 is a back view of the new design.

FIG. 4 is a bottom view of the new design.

FIG. 5 is a front view of the new design.

FIG. 6 is a left side view of the new design; and,

FIG. 7 is a right side view of the new design.

The broken or dashed lines shown in the drawings are for illustrative purposes only and form no part of the claimed design.

1 Claim, 3 Drawing Sheets

FIG. 4
